UNITED STATES PATENT OFFICE.

FREDERICK W. SCHMITHALS, OF MILWAUKEE, WISCONSIN, ASSIGNOR TO BUCYRUS COMPANY, OF SOUTH MILWAUKEE, WISCONSIN, A CORPORATION OF WISCONSIN.

STEAM-SHOVEL-OPERATING MECHANISM.

1,286,426.

Specification of Letters Patent.

Patented Dec. 3, 1918.

Application filed July 11, 1917. Serial No. 179,813.

To all whom it may concern:

Be it known that I, FREDERICK W. SCHMITHALS, a citizen of the United States, residing at Milwaukee, in the county of Milwaukee and State of Wisconsin, have invented a certain new and useful Improvement in Steam-Shovel-Operating Mechanism, of which the following is a specification.

10 My invention relates to means for operating and controlling boom engines for steam shovels and the like. I have illustrated a part of a steam shovel showing the boom the forward end of the car body upon which 15 the boom is pivoted and the thrusting engines on the boom. The other parts are not needed in order to make my invention clear and I have, therefore, omitted them.

It will be understood that the operator 20 ordinarily stands upon the car to control the hoisting and swinging engines which form an essential part of the apparatus itself but which are not here illustrated and that another operator usually is placed upon 25 the boom to control the thrusting engines in coöperation with the operator on the car, that is two operators under ordinary circumstances are needed to coöperate to control the engine. My invention is adapted 30 to do away with the need of the second operator and it deals specifically with means for enabling the one operator from a station on the car to control both the swinging and hoisting engines and the thrusting 35 engines on the boom. This makes it possible to arrange the controls coördinately so that one man may control them all and so that the human equation is reduced to its least possible minimum.

40 My invention is illustrated more or less diagrammatically in the accompanying drawings wherein—

Figure 1 represents detailed diagrammatic side elevation of the forward portion 45 of a steam shovel car and fragment of the boom pivoted thereon;

Fig. 2 is a detailed diagrammatic plan view of a part of the boom with the thrusting engines mounted thereon and showing 50 the connecting mechanisms the boom being here shown in its central position;

Fig. 3 is a partial plan view similar to Fig. 2 with the boom swung to one side;

Fig. 4 is a detailed side elevation of a 55 modified form.

Like parts are indicated by like characters in the drawings:

A represents a car body or other platform.

B represents a swinging boom, swinging 60 about a vertical axis XX, and mounted upon swing circle C, which revolves upon a pintle attached to the car body. B¹ is the thrusting engine, which is controlled as to speed, and reversed, by means of a distribution 65 valve not shown, but which is operated by the valve stem B², through a shaft and bell cranks B³, reach rod B⁴, and lever B⁵, keyed upon shaft B⁶. Shaft B⁶ is supported by two bearings B⁸ located on opposite sides 70 of the boom structure, and between these two bearings are keyed to the shaft B⁶ the two levers B⁹, extending preferably when in central position in a horizontal direction. Directly above the two levers B⁹ are two 75 extending arms of a bent strap B¹⁰, which is fulcrumed upon the transverse bolt B⁷. The bolt B⁷ is vertically above the shaft B⁶ and the two projecting arms of the bent strap B¹⁰ are located directly above the two 80 projecting levers B⁹ and are of the same length. Each lever B⁹ is connected to the corresponding arm of strap B¹⁰, which is vertically above it, by a bar B¹¹. The two vertical bars B¹¹ are therefore widely separated as shown, and a single U-shaped strap 85 B¹², having its closed end bent to a semi-circular form, is rigidly secured to the two arms B¹¹, being in effect integral therewith.

The center of curvature of strap B¹² is 90 located on the vertical axis XX of the swing circle C, about which axis the boom revolves. The swing circle and base plate thereunder are formed with a large opening through which passes the hoisting chain 13. 95 This chain must be free to operate in any position of the boom, and it is obvious that the above described construction of the bent strap B¹² leaves an opening through which the chain may freely pass.

100 The semi-circular part of strap B¹² is engaged by one arm of the bell crank C¹⁴, the other arm being connected by a reach rod C¹⁵ to the operating lever C¹⁶. It may be necessary to regulate the speed or direction 105 of the thrusting engine B¹ upon the boom in any swinging position of the boom. The boom swings through a total angle of about 180°, or a semi-circle, and it is obvious from Figs. 2 and 3 showing the boom in its cen- 110

tral position parallel to the car-body and also swung through an angle of 45° , that the semi-circular portion of strap B^{12} engages the jaw in bell crank C^{14} , irrespective 5 of the angular position of the boom. This is because the rotation of the platform carrying the boom merely causes the semi-circular loop to slide along between the jaws on the end of the bell crank lever without 10 interfering with the connection between them.

In the modified form shown in Fig. 4 the bell crank lever B^9 is slotted as at D and slidably engages a pin D^1 in the sliding bar 15 D^2 which bar is free to slide in the bearings D^3 D^4 . D^5 is a similar semi-circular strap extending rearwardly from two such bars D^2 and curved about the axis of rotation of the member C so as to be concentric therewith. This strap D^5 rotates within the jaws of the bell crank lever C^{14} .

The use and operation of my invention are as follows:—

Referring first to the preferred form 25 shown in Fig. 1, I have indicated the arcs through which the ends of the bell crank levers B^9 and links B^{10} travel in dotted lines as indicated. Since the lines joining the pivot points of each end of these levers are 30 parallel, the levers will have a parallel movement and the members B^{12} will move up and point in a horizontal plane. The curved member being mounted on the boom support will rotate with it and this curved member will travel back and forth through the 35 jaws of the bell crank lever and will be in operative engagement with such jaws no matter what the position of the turn table upon which the boom is mounted.

Therefore, any movement of the lever C^{16} 40 will result in a proportional movement of the throttle valve stem B^2 no matter what the position of the boom at the time the movement was made, also, subsequent swinging 45 of the boom after a given adjustment of the throttle lever stem is accomplished will not change that adjustment and thereby cause movements of the thrusting engine which were not intended.

In the modified form shown in Fig. 4, the 50 situation is exactly the same except that the parallel movement is provided by means of the sliding bar which is held in a permanent vertical position by the guide bearings therefor. There may be one or more of 55 these bars and the curved segment strip will be mounted upon them in the usual manner as shown, the operation being exactly the same as in connection with the preferred form shown in Fig. 1. 60

I claim:—

1. In a steam shovel, a working platform, a swinging boom machinery mounted on the boom, an operating mechanism for controlling the boom machinery from the car body, 65 an extension therefrom concentric with the axis of rotation of the boom, a lever in operative engagement with such arcuate member and means for maintaining such arcuate member in position in a plane normal to 70 such axis of rotation comprising a plurality of links, a base upon which they are pivoted, an arm supported by them and carrying such arcuate member.

2. The combination with a working platform of a swinging beam mounted thereon and working mechanism on the beam of an operating lever, connection between such working mechanism and the operating lever comprising two separate co-operating members one member being a lever mounted on the platform with a fork end which loosely engages the other member, the other being an arcuate member concentric with the axis of rotation of the beam, said member being 80 rigidly mounted on a rocking member parallel to the axis of rotation of the beam, a lever controlled by said rocking member having pivoted to its free end a shaft controlling the working mechanism. 85

In testimony whereof, I affix my signature in the presence of two witnesses this 22nd day of June, 1917.

FREDERICK W. SCHMITHALS.
